UNITED STATES PATENT OFFICE.

REINHOLD HOPPE, OF SAN FRANCISCO, CALIFORNIA.

SURGICAL SPLINT.

SPECIFICATION forming part of Letters Patent No. 504,218, dated August 29, 1893.

Application filed February 10, 1893. Serial No. 461,802. (No model.)

To all whom it may concern:

Be it known that I, REINHOLD HOPPE, a citizen of the United States, residing in the city and county of San Francisco, State of California, have invented an Improvement in Mechanical Surgical Splints; and I hereby declare the following to be a full, clear, and exact description of the same.

My invention relates to a device which I call a mechanical surgical splint.

It consists of supporting plates with rods upon which they are adjustable, and jointed connecting rods attached thereto, with adjusting and regulating screws whereby the plates may be set to any desired position with relation to each other; and in certain details of construction which will be more fully explained by reference to the accompanying drawings, in which—

20 Figure 1 shows its application to the outside of a joint. Fig. 2 is a view showing the apparatus in position to be used upon the inside of a joint. Fig. 3 is a section showing the construction of the screw and sleeve. Fig. 25 4 illustrates its application to the back.

The object of this invention is to provide in a simple instrument, a splint which may be used upon fractured limbs or upon the back where there is a curvature which needs gradual straightening and strengthening, and for various other injuries or malformations to the human body.

The device is so constructed that the supporting plates may be fitted upon the outside 35 of a joint, as in the case of an elbow or knee joint, or upon the inside, or upon either side thereof, the plates being movable upon supporting rods to fit any form and shape or position, to which it is desired to set the apparatus, and for any desired pronation.

In the present case I have illustrated my invention as applied to a splint especially adapted for the support of broken bones, and injuries near the joints.

45 A and B are two plates made of any suitable or desired material. In some cases wood may be employed, but I have found that the metal aluminum is very suitable for the purpose, being light and easily manipulated.

50 C C' are two rods having a hinge joint D by which they are connected together.

E E are two sleeves adapted to slide and

turn upon the rods C C', and these sleeves are permanently fixed to the backs of the plates A and B.

55

There are set screws passing through the sleeves, by which they are secured to the rods in any desired position, the sleeves turning freely about the rods, or slipping along them, and being afterward secured by the set screws. 60 From each of the rods a standard G projects approximately at right angles as shown, and the outer ends of these standards are slotted, one to receive the end of a screw shank I, and the other the end of a tubular rod H.

65

J is a nut through which the screw I passes. This nut is contained within a cylindrical casing J', the sides of which are cut away, or may turn between stationary collars, so that the finger and thumb may grasp the nut upon 70 opposite sides and turn it, and this causes the nut to advance or retreat upon the screw. An extension of the casing J' is hinged to the adjacent end of the tubular rod H which is hinged, as before described, to the standard G', and when the nut is turned to move the screw out of it, the action of the two jointed parts J' and H will be to turn the rods C C' about their hinge, and thus bend the plates into the position shown in Fig. 1. 75 When the screw is moved in the opposite direction, the tendency will be to shorten the distance between the standards G G', and thus to bend the rods C C' about their joint into the position shown in Fig. 2.

85

Upon the rod H is fitted a sleeve L having a slot M made in it, which fits over a pin N fixed to the tubular rod H and projecting out through the slot so as to act as a guide when the sleeve is moved longitudinally upon the 90 tubular rod H, and to lock the parts when it is turned into a transverse part of the slot at one end. When moved in one direction, this sleeve slips over the joint K, at which point the rod H and the sleeve J' are hinged together, and thus retains these two parts in a straight line, so that when the screw is turned to enter the nut J and shorten the distance between the two standards G, the screw will pass into the tubular rod H in a straight line, 95 and as the distance between the posts G G' is shortened by thus shortening the connection, the two rods C will be bent about their hinge point at D until the plates A and B take any

100

position with relation to each other, as shown in Fig. 2, so that the splint may be fitted upon the inner side of a joint, such as the elbow or knee joint. It will be seen that as the rods 5 C C' bend about their joint D, the connection between the standards G and G' is shortened by advancing the nut J upon the screw I, and as this connection thus becomes shortened the joint D is moved away from the central 10 portion, so that the two rods C C', the tubular sleeve and screw I which form the connection between the standards G and G' will form a triangle which may occupy any position from one in which the joint D forms a right angle, 15 to a position in which it forms a very slightly obtuse angle.

When it is desired to flex the apparatus in the opposite direction, as shown in Fig. 1, the sleeve L is slipped along the tubular rod H, 20 being guided by the pin N until the sleeve has been slipped clear of the joint K, leaving it free to turn. When this point has been reached an eye O which is formed upon the sleeve L slips over a hook P which is secured 25 to the rod C', and this locks the sleeve to the rod C'. The joint K is then free to turn, and as the nut J is advanced toward the point of the screw I, the latter is withdrawn from the tubular sleeve II, and this allows the latter to 30 be turned out of line with the screw as shown in Fig. 1, and the hinge rods C and C' then bending about their joint D in the opposite direction to that formerly described, will occupy a position as shown in Fig. 1, in which 35 case, as before, any desired angle between the two plates A and B may be obtained, and this allows the plates to be fitted upon the outside of the joint. If the plates are to be fitted upon either side of a joint, it is done by loosening the screws F and turning the sleeves E 40 about the rods C, thus setting the plates A and B so that they may fit upon the side of the arm or other member, instead of at the front or rear of the joint, as previously described. By this construction I am enabled 45 to turn the apparatus into every possible position which may be needed, and when it is fixed in either of these positions, it is perfectly rigid, and will hold the member to which 50 it is attached in that position as long as may be desired.

It will readily be seen that in cases of joint fracture where it is necessary that the joint be moved a little each day such a device is 55 invaluable, as by turning the screw I a little ways each day, the joint may be moved in the corresponding direction as far as may be desired, and it may be then returned in the opposite direction, thus keeping the joint from 60 becoming stiff, while at the same time the broken or splintered bone, which is close to the joint, is held sufficiently rigid to allow it to knit and become strong.

By applying the screw with its nut, sleeve 65 and jointed rods to apparatus which is fitted to the back in case of spinal curvature, round shoulders, or other deformity, it will be seen

that the screw can be turned a little each day and thus gradually correct the difficulty.

The apparatus is applicable to all forms of 70 orthopedical work.

Having thus described my invention, what I claim as new, and desire to secure by Letters Patent, is—

1. A surgical splint consisting of rods having 75 their meeting ends hinged together, plates adapted to fit the part to be treated having sleeves fixed to their backs, and slidable and rotatable upon the rods, and set screws whereby the sleeves and plates are held in any desired position upon the rods, slotted standards projecting from the rods at points intermediate between the ends, a screw, the shank of which is hinged to one of said standards, and a tubular rod having one end hinged to the 85 opposite standards, a nut turning within a casing, one end of which is hinged to the tubular rod, whereby the nut may be advanced along the screw to lengthen the connection between the standards, and thus bend the 90 hinged rods and their attached plates to form an internal angle, substantially as herein described.

2. A surgical splint consisting of rods having 95 their meeting ends hinged together, plates adapted to fit the part to be treated, having sleeves secured to their backs and slidable and rotatable upon the rods, set screws whereby the sleeves and plates are secured in any desired position, slotted standards projecting 100 from the rods at points intermediate between their ends, a screw, the shank of which is hinged to one of said standards, a tubular rod H, the outer end of which is hinged to the other standard, a casing having one end hinged 105 to the inner end of the tubular rod, a nut adapted to be turned within the casing, said nut being advanced in either direction along the screw by turning it, a sleeve slidable upon the tubular hinged rod and adapted to slip 110 over the end of the casing containing the nut whereby the casing is retained in a straight line with the tubular rod, so that when the nut is advanced along the screw to shorten the distance between the standards, the screw 115 will enter the tubular rod, and the hinged rods are turned about their joints so that the plates form an exterior angle with each other, substantially as herein described.

3. A surgical splint consisting of rods 120 hinged together at their meeting ends, plates adapted to fit the part to be treated having sleeves secured upon their backs slidable and rotatable upon the outer ends of the rods, slotted standards projecting from the rods at 125 points intermediate between their ends, a screw, the shank of which is hinged to one of the standards, a tubular sleeve, the outer end of which is hinged to the opposite standard, a case containing a nut rotatable therein so 130 as to advance it along the screw in either direction, said case being hinged to the adjacent end of the tubular rod, a sleeve L slidable upon the tubular rod having an eye O

formed upon it and a hook P fixed to one of the hinged rods over which this eye is adapted to slip and retain the tubular sleeve in position parallel with the rod to which it is connected while the plates are turned so as to form an interior angle between them, substantially as herein described.

In witness whereof I have hereunto set my hand.

REINHOLD HOPPE.
